HARNESS MOTIONS

Leland D. Cobb, Forestville, Conn., assignor to
 Draper Corporation, Hopedale, Mass., a corpora-
 tion of Maine

Application June 7, 1945, Serial No. 598,062

4 Claims. (Cl. 139—79)

1

The present invention relates generally to shedding mechanisms for looms and, as illustrated herein, relates more particularly to the cam type of such mechanisms.

Looms of the type to which the present invention pertains are provided with a plurality of harness frames which are reciprocated by harness treadles which in turn are reciprocated about a fixed axis by suitable cams. In order to keep the warp opening as small as possible, it has heretofore been necessary to provide a large number of sizes of harness cams, both for equipping new looms and for replacement purposes to adapt existing looms to different weaving conditions. The investment in harness cams, accordingly, has necessarily been rather high and it has been proposed to provide a shedding mechanism wherein a plurality of warp openings of different widths are formed by the use of a single cam. The construction disclosed and claimed in the patent to Brown No. 2,042,422, granted May 26, 1936, has successfully solved this problem. In this construction the fulcrum member comprises an elongated gear member meshing with teeth formed on the various treadle members and adjustment of the elongated gear member varies the fulcrum point and thus controls the extent of the warp opening.

The above mentioned construction is satisfactory under practically all conditions of use but in some instances positive control of the extent of warp opening is desired within very close limits and the above construction is unsatisfactory therefore because of lost motion between the parts. This lost motion is a result, in part at least, of movement of the elongated gear member which consequently varies the fulcrum point.

It has been proposed to lock the elongated gear member in adjusted position by the use of locking screws entering between the gear teeth and thus preventing undesired angular movement thereof. This method of locking the gear member was disclosed and claimed in U. S. Patent No. 2,356,713, granted August 22, 1944, in the name of James M. Tuten. This construction securely locked the gear member in position but after a period of use the locking screw of the gear member would become worn, thus necessitating further adjustment and tightening of the locking screws.

One object of the present invention is to provide a construction whereby said lost motion will be substantially reduced under all conditions. To this end the elongated gear member is locked in adjusted position by clamping the gear member against supporting brackets. By loosening

2

the clamping means, the elongated gear member is ready for adjustment and, when the adjustment has been made, the clamping means is again tightened thus locking the elongated gear member in position. The abutting contact surfaces occupy a substantial area and, hence, wear is reduced to a minimum.

With the above and other objects and features in view, the invention will be described with particular reference to the accompanying drawings which illustrate a preferred embodiment of the invention and in which:

Fig. 1 is a view, partly in section, of a portion of a loom in which the present invention is embodied;

Fig. 2 is an enlarged detail view of the clamping mechanism;

Fig. 3 is a plan view of the mechanism shown in Fig. 1;

Fig. 4 is a view in section taken along the line IV—IV of Fig. 3; and

Fig. 5 is a view in section taken along the line V—V of Fig. 3.

The loom shown in the drawings, except for the shedding mechanism, is of a conventional construction and, accordingly, is but fragmentarily illustrated. The conventional right-hand loom side 10 is connected to a left-hand loom side by a plurality of cross members, as by the cross girt 12. The front of the loom is at the right of Fig. 1 of the drawing. The loom has a crank shaft 14, and a cam shaft 16 carrying a plurality of cams 18.

The present construction includes the usual arrangement of harness frames 20 which extend substantially vertically and widthwise of the loom and are arranged to be reciprocated vertically by the cams 18 and harness treadles 22 positioned below the harness frames. In the drawings only one harness is shown but a plurality of such harnesses are obviously necessary. These harnesses are positioned parallel to each other. The harness treadles 22 are positioned parallel to each other and extend rearwardly from the general plane of the collection of harness frames 20. The forward end of each treadle 22 is connected to a harness frame by any usual means, such, for example, as a harness strap 24.

The rotating harness cams 18 are located above the treadles 22 and intermediate the ends thereof. Each cam 18 depresses its associated treadle 22 through engagement with a roller 26 carried by the treadle. The harness treadles are fulcrumed at their rearward ends and depression of a treadle 22 results in the connected harness frame being depressed and which corresponds to

the throw of the forward end of the treadle. The harness is returned to its initial position by any usual type of top motion such as disclosed, for example, in the patent to Bell, No. 1,580,948, granted April 13, 1926.

The fulcrum for the treadle comprises an elongated gear member 28 having teeth 30 extending transversely of the treadle and meshing with rack teeth 32 formed on the treadle 22. The gear member 28 is sufficiently elongated to engage and support all of the harness treadles used on a loom. The treadles rock on the gear member which, as will later be described, is normally held in fixed position. The gear member 28 may be shifted longitudinally of the treadles without shifting the treadles to vary the fulcrum point and thus simultaneously and equally vary the throw of the treadles. Thus the size or extent of the warp opening may be widely varied without changing the harness cams.

The elongated gear member 28 is adjustably supported in brackets 34, 36 which are bolted to middle girts 38, 40. The brackets 34 and 36 are substantially identical except that they are right and left hand and, hence, it will be necessary to describe only one of the brackets. The bracket 34 is provided with a rack 42 having teeth 44 which mesh with the teeth 30 on the elongated gear member 28. When the gear member 28 is rotated with the teeth 30 in mesh with the teeth 44 on the rack 42, the member 28 will move bodily forwardly or rearwardly relatively to the brackets 34 and 36. The gear member 28 at each end is provided with an opening through which a bolt 46 passes, the bolts 46 forming the axis about which the gear member 28 rotates. The bolt 46 extends through a supporting member 48 having a laterally extending portion 50 fitting into a slot 52 formed in the bracket 34. The portion 50 is rectangular in transverse section and, hence, will not rock in the slot 52. The supporting member 48 is provided with a forwardly extending substantially horizontal arm 54 having a longitudinal slot 56 at its forward end portion. A bolt 58 passes through a hole in the bracket 34 and through the slot 56. When the nut 60 is tightened, the member 48 is locked in adjusted position.

In the use of the above construction, the elongated gear member 28 may be quickly and easily adjusted to provide for various sizes of shed openings and locked in adjusted position. The bolts 46 on each end of the elongated gear member 28 are loosened. The bolts 58 which lock the supporting members 48 in adjusted position are also loosened, thus permitting rotation of the elongated gear member 28 forwardly or rearwardly, as desired. The harness treadles 22 are normally restrained from longitudinal movement and hence when the elongated gear member 28 is rocked, the fulcrum point of the harness treadles 22 is varied. When the gear member 28 has been moved to the desired location the bolts 46 and 58 are tightened to lock the gear member 28 firmly in adjusted position. The bolts 46 firmly clamp the elongated gear member 28 to the supporting members 48 and since there is a substantial area of contact between the contacting surfaces wear is reduced to a minimum. Forward and rearward movement which would be permitted by the necessary back lash between the gear teeth 30 and 44 is effectively prevented by the bolts 58 which clamp the supporting member 54 to the supporting brackets 34 and 36.

Having thus described my invention, what I

claim as new and desire to secure by Letters Patent of the United States is:

1. In a loom, a harness frame, a harness treadle connected with said frame for operating the latter, a cam for operating the treadle, a gear member on which said treadle is fulcrumed, said gear member having gear teeth extending transversely of said treadle and meshing with gear teeth formed thereon, support means at each end of the gear member supporting the gear member for rolling movement longitudinally of said treadle to adjust the fulcrum point of the treadle, said support means including adjustable relatively fixed structure and means frictionally locking said gear member to said fixed structure.
2. In a loom, a harness frame, a harness treadle connected with said frame for operating the latter, a cam for operating the treadle, a gear member on which said treadle is fulcrumed, said gear member having gear teeth extending transversely of said treadle and meshing with gear teeth formed thereon, individual support structures one at each end of said gear member supporting the gear member for rolling movement longitudinally of said treadle to adjust the fulcrum point of the treadle, each of said support structures comprising an adjustable relatively stationary part and means frictionally locking said gear to said stationary part.
3. In a loom, a harness frame, a harness treadle connected to the frame for operating the latter, a cam for operating the treadle, a gear member on which the treadle is fulcrumed, said gear member having gear teeth extending transversely of said treadle and meshing with rack teeth formed on said treadle, said gear member having plane parallel end portions, movable means for supporting the gear member for rolling movement longitudinally of the treadle to adjust the fulcrum point of the treadle, stationary brackets in which said movable supporting means are slidably mounted, said means including means frictionally locking each of said end portions of said gear to a respective one of said stationary brackets.
4. In a loom, a harness frame, a harness treadle connected to the frame for operating the latter, a cam for operating the treadle, a gear member on which the treadle is fulcrumed, said gear member having gear teeth extending transversely of said treadle and meshing with rack teeth formed on said treadle, said gear member having plane parallel end portions, movable means for supporting the gear member for rolling movement longitudinally of the treadle to adjust the fulcrum point of the treadle, stationary brackets in which said movable supporting means are slidably mounted, said movable means comprising support members and bolts, each of said bolts extending through one of said end portions and through one of said movable supporting members for locking the gear member against rotation in adjusted position, and means for locking said movable supporting members in position on said stationary brackets.
